UNITED STATES PATENT OFFICE

ALFRED J. GRUBER, OF ATLANTA, GEORGIA

HEEL PROTECTOR OR SHIELD

Application filed July 20, 1931. Serial No. 552,042.

This invention relates to a shield or protector for the heels of shoes and particularly the usual high heels of ladies' shoes, to prevent soiling thereof or contact of the outer surface with pedals or the like, as encountered in operating an automobile for example.

A particular object is to provide an article accomplishing the end stated, which may be made from a single piece or stamping of resilient sheet metal, and which may be attached of itself, that is without the aid of any extraneous fastening, such as a nail or screw.

15. It is further aimed to provide a preferably one-piece article of the character stated wherein heel engaging flanges perform the further functions of gripping means for the fingers, prevent distortion of the shield and cause the same to yield from the rear along a substantially central line, in order to move attaching spurs to and from a position between the counter and upper lift of the heel, said flanges and spurs also coacting to prevent vertical and lateral movement of the shield relatively to the heel when the shield is in place.

The more specific objects and advantages will become apparent from a consideration of the description following taken in connection with the accompanying drawings illustrating a preferred embodiment and wherein—

35. Fig. 1 is a fragmentary side elevation of a lady's shoe having the heel equipped with the improved shield.

Fig. 2 is a vertical sectional view taken on the line 2, 2 of Fig. 1, and

40. Fig. 3 is a detail perspective view of the shield.

Referring specifically to the drawings, 10 designates a conventional lady's shoe having a heel at 11 depending from the counter 12 above which the upper lift 13 is provided.

45. The shield constituting the present invention comprises a metallic body which is preferably a single piece or stamping of resilient sheet metal, for instance copper, although no limitation as to material is to be implied. The body 14 may be lined if de-

sired either interiorly or exteriorly, or completely covered.

Said body 14 is generally arcuate in horizontal section so as to conform to the shape of the heel, the body being open at the front 55 of the heel and at top and bottom. The upper edge 15 of the body conforms in shape to the line of junction between the upper lift 13 and counter, and the forward ends thereof terminate in inwardly extending attaching 60 spurs 16 which, as well shown in Fig. 2, extend or wedge into the space at said junction line between the counter 12 and upper lift 13, and overhang said counter 12.

Said spurs 16 project forwardly a considerable distance beyond the front wall of the heel, and the lower edge portions of the shield are provided with elongated flanges 17 adapted to engage against the front wall 65 70 of the heel.

The normal position of the shield is shown in Fig. 3. When the same is applied to the heel, the fingers of the hands of the user engage the flanges 17 and are manipulated to move the flanges apart, thereby springing 75 the shield along a substantially vertical line centrally of the rear thereof, whereby not only the flanges 17 but the spurs 16 are spread apart.

In this condition, the shield is applied to 80 the heel and thereupon released, so that the spurs 16 due to the fact that the shield is elastic will occupy the position of Fig. 2, preventing downward displacement of the shield, and the flanges 17 will engage the front wall of the heel, preventing lateral displacement of the shield.

The shield as a whole thus conforms intimately with the shape of the engaged wall 90 of the heel, and has a clasping and retaining pressure thereagainst.

The shield is preferably made from relatively thin sheet metal, and to this end the flanges 17 are relatively long as shown. Such 95 flanges in addition to forming attaching means, also provide finger grips or engaging portions, and further prevent distortion of the body 14 through bending, and on the contrary insure the separation and spring ac- 100

tion of the body from the central rear vertical line as set forth.

Various changes may be resorted to provided they fall within the spirit and scope 5 of the invention.

I claim as my invention:

1. A shield for a shoe heel comprising a flexible and elastic body of heel-shape open at the breast portion thereof and devoid of 10 flanges along the upper and lower edges, said body having spurs at the upper forward ends adapted to enter between the counter and upper lift of a shoe, said body having flanges at the forward edges adapted for engagement 15 with the breast of the heel.
2. A shield for a shoe heel comprising a one piece sheet of thin flexible and elastic metal of heel-shape open at the breast thereof and devoid of flanges along the upper 20 and lower edges, said body having integral spurs at the upper forward ends adapted to enter between the counter and upper lift of a shoe, said body having integral elongated upright flanges at the forward edges rear- 25 wardly of the spurs adapted for engagement with the breast of the heel.
